(57) **CLAIM**

We claim the ornamental design for a outdoor accent light, as shown and described.

DESCRIPTION

FIG. 1 is a perspective view of the accent light showing our new design;

FIG. 2 is a left side elevational view of the accent light, the right side elevational view being a mirror image;

FIG. 3 is a front elevational view of the accent light;

FIG. 4 is a rear elevational view of the accent light;

FIG. 5 is a top plan view of the accent light; and,

FIG. 6 is a bottom plan view of the accent light.

The broken lines shown are for illustrative purposes only and form no part of the claimed design.
